LEVER FOR LOOM PATTERN MECHANISM

William A. Blanchard, Millbury, Mass., assignor
to Crompton & Knowles Loom Works, Worcester, Mass., a corporation of Massachusetts

Application June 6, 1946, Serial No. 674,810

7 Claims. (Cl. 139—77)

1

This is a continuation in part of my copending application Serial No. 615,123, filed September 8, 1945.

This invention relates to improvements in pattern mechanism levers for looms and more particularly to the vibrator levers used in the well-known Knowles head.

Vibrator levers for the Knowles head and other types of harness operating mechanisms have heretofore been made of solid pieces of metal, generally malleable iron. Such levers are heavy and are likely because of their weight to cause wearing of the parts which support them and also the pattern chains which operate them. It is an important object of my present invention to make the vibrator lever with top and bottom rails between which is located a sinuous reinforcing wire or the like extending for the greater part of the length of the lever and welded or otherwise secured to the rails.

The vibrator lever ordinarily has several parts, such as a heel pin bearing at one end, a lock knife lug at the other end, and a pattern chain run and vibrator gear bearings intermediate its ends. It is a further object of my present invention to secure these parts to the rails in such manner that they will be held in proper position for cooperation with the several loom parts which engage them.

With these and other objects in view which will appear as the description proceeds, my invention resides in the combination and arrangement of parts hereinafter described and set forth.

In the accompanying drawing, wherein two forms of the invention are shown,

Fig. 1 is a side elevation of a vibrator lever made according to the preferred form of my invention,

Fig. 2 is a plan view of the vibrator lever looking in the direction of arrow 2, Fig. 1, the vibrator gear, its connector, and the lock knife being omitted.

Fig. 3 is an enlarged vertical section on line 3—3 of Fig. 1,

Fig. 4 is a bracketed view showing a side and end elevation of the heel pin bearing,

Fig. 5 is a bracketed view showing a side elevation and end view of the pattern chain run,

Fig. 6 is a side elevation of the top rail shown in Fig. 1,

Fig. 7 is a plan view looking in the direction of arrow 1, Fig. 6,

Fig. 8 is a side elevation of the bottom rail,

Fig. 9 is a plan view looking in the direction of arrow 9, Fig. 8,

2

Fig. 10 is a side elevation of a vibrator lever made according to the modified form of the invention, and

Figs. 11 and 12 are enlarged vertical sections on lines 11—11 and 12—12, respectively, of Fig. 10.

Referring particularly to Fig. 1, I have shown a vibrator lever V supported at its left end on a heel pin H and having a pattern run P, a vibrator gear G, and a gear connector C. A lock knife K operated by the loom cooperates with a lock knife lug L at the right end of the lever to lock the latter either in its down or up position as determined by the pattern chain 10. The latter is provided with rolls ordinarily of two different diameters so that when a small roll is under the run P the vibrator lever will be down, but when a large roll is under the run the lever will be up. The gear cooperates with well-known mutilated top and bottom gear cylinders not shown herein. All of the foregoing, except as pointed out hereinafter, is of the usual relationship found in the well known Knowles head.

In carrying the preferred form of my invention into effect I provide the vibrator lever V with top and bottom rails 15 and 16, respectively, which extend between the heel pin bearing 17 and the lock knife lug L. A sinuous metallic reinforcing member 19 formed preferably of wire extends between the rails 15 and 16 and has its various bends welded or otherwise secured to the rails.

The heel pin bearing 17 is provided with a downwardly opening slot 20 to receive the heel pin H, and has a notch 21 to receive the left end of the upper rail 15. A side notch 22 formed in the bearing 17 receives the upwardly bent left end 23 of the bottom rail 16.

Adjacent to the right end of the top rail there is an upwardly opening notch 25 which receives the bearing 26 for the vibrator gear G. The bearing 26 is welded or brazed to the top rail 15, and the right end of the latter extends along and is welded to the top of lug L.

The intermediate part of the lower rail 16 is bent downwardly as at 30 and then horizontally as at 31 to be welded or otherwise secured to the lower edge of the lug L. The pattern run P is formed with a flat vertical web 32, the lower end of which is provided with a broadened concave chain engaging edge 33. The left side of the web 32 as shown in Fig. 5 is provided with a wing 34 which is bent at right angles to the web to lie against the part 30 of the bottom rail and be welded thereto. The web extends along part of 50 the member 19 and is welded thereto, and also

extends along the left hand part of the straight or horizontal section 31 of the lower rail and is welded thereto. The run is thus held firmly in position not only by its engagement with two angularly disposed parts of the lower rail 16 but also by certain of the bends of the sinuous member 19.

In the modified form of the invention the heel pin bearing 17 may be the same as that used in the preferred form of the invention, and the top rail 40 may be similar to rail 15. The bottom rail 41, however, while having its left end formed in a manner similar to the left end of rail 16, has its intermediate part 42 curved downwardly to the right hand horizontal end 43. The pattern run P' has a concave edge 44 similar to edge 33, a horizontal right end 45, and a vertical part 46 to the left of edge 44 terminating in a horizontal left end 47. The run P' has its parts 45 and 47 recessed, see Figs 11 and 12, to receive and be welded to the lower rail 41.

Located between the lower rail 41 and the member 45 is a metallic sinuous reinforcing member 58 which connects the part 42 of the rail 41 to the run P'. Extending between the rails 40 and 41 is a second reinforcing metallic sinuous member 51.

In both forms of the invention the vibrator lever may be provided with a stop 55 to be received by an arcuate slot 56 in the gear G, and this stop is preferably secured to the lock knife lug L.

In operation, the pattern chain 10 moves under the pattern run and either raises or lowers the vibrator lever, depending upon the size of the chain roll in engagement with the runs 33 or 44. Levers V and V' move angularly around the heel pin H to effect vertical movement of the vibrator gear G. Engagement of the latter with one or the other of the previously mentioned but not shown mutilated cylinder gears effects horizontal motion of the connector C.

From the foregoing it will be seen that I have provided a simple form of pattern lever light in weight and made of top and bottom rails between which extend reinforcing sinuous metallic members which are welded or otherwise secured to the rails. The pattern run in each form of the invention is connected to the bottom rail, and in the preferred form is additionally connected to certain of the bends of the sinuous member 19, whereas in the modified form a supplementary reinforcing member 50 is interposed between the pattern run P' and the bottom rail 41. All the parts of the vibrator lever are secured together as by welding, brazing, silver soldering or the like so that the lever becomes in effect an integrated unit possessing considerable strength but being comparatively light in weight.

Having thus described my invention it will be seen that changes and modifications may be made therein by those skilled in the art without departing from the spirit and scope of the invention and I do not wish to be limited to the details herein disclosed, but what I claim is:

1. In a loom pattern mechanism vibrator lever, a pair of vertically spaced tie rods extending lengthwise of the lever, a heel pin bearing secured to said tie rods adjacent one end of the lever, a lock knife lug secured to said tie rods

adjacent the other end of the lever, a pattern chain run on the lower tie rod, and a reinforcing wire of sinuous form extending between and secured to said tie rods.

2. In a loom pattern mechanism vibrator lever, a pair of vertically spaced tie rods extending lengthwise of the lever, a bearing member secured to said tie rods adjacent one end of the lever, a pattern chain run on the lower tie rod, and reinforcing wire means of sinuous form extending between and secured to said tie rods, part of said reinforcing wire means being over said pattern chain run.

3. In a loom pattern mechanism vibrator lever, a pair of vertically spaced tie rods extending lengthwise of the lever, a heel pin bearing secured to said tie rods adjacent one end of the lever, a lock knife lug secured to said tie rods adjacent the other end of the lever, a reinforcing wire of sinuous form extending between and secured to said tie rods, and a pattern chain run secured to the lower tie rod and to parts of the reinforcing wire.

4. In a loom pattern mechanism vibrator lever, a pair of vertically spaced tie rods extending lengthwise of the lever, a bearing member secured to said tie rods adjacent one end of the lever, a reinforcing wire of sinuous form extending between and secured to said tie rods, and a pattern chain run secured to the lower tie rod and to parts of said reinforcing wires.

5. In a loom pattern mechanism vibrator lever, a pair of vertically spaced tie rods extending lengthwise of the lever, a bearing member secured to said tie rods adjacent one end of the lever, a reinforcing wire of sinuous form extending between and secured to said tie rods, and a pattern chain run having a web secured to the lower tie rod and parts of the reinforcing wire and having a concave pattern chain engaging edge extending laterally from the web under the lower tie rod.

6. In a loom pattern mechanism vibrator lever, a pair of vertically spaced tie rods extending lengthwise of the lever, a bearing member secured to said tie rods adjacent one end of the lever, a reinforcing wire of sinuous form extending between and secured to said tie rods, a pattern chain run secured to the lower tie rod and having a part thereof spaced below said lower tie rod, and a second reinforcing wire of sinuous form between the lower tie rod and said part of the pattern chain run.

7. In a loom pattern mechanism vibrator lever, a pair of vertically spaced tie rods extending lengthwise of the lever, a bearing secured to said tie rods adjacent one end of the lever, a lock knife lug secured to said tie rods adjacent the other end of the lever, a reinforcing wire of sinuous form extending between said bearing and lug and extending also between and secured to said tie rods, a pattern chain run secured to and depending from the lower tie rod intermediate said bearing and lug and having a part thereof spaced below the lower tie rod, and a second reinforcing wire of sinuous form extending between the lower tie rod and said part of the pattern chain run.

WILLIAM A. BLANCHARD.
